UNITED STATES PATENT OFFICE.

EVA LEPOW, OF PHILADELPHIA, PENNSYLVANIA.

STOCKING.

Application filed November 2, 1921. Serial No. 512,173.

To all whom it may concern:

Be it known that I, EVA LEPOW, a subject of the King of Rumania, residing at Philadelphia, in the county of Philadelphia 5 and State of Pennsylvania, have invented certain new and useful Improvements in Stockings, of which the following is a specification.

Usually the first place in a child's stocking that becomes worn is at the knee, all other portions of the stocking being in good condition with exception of the knee portion. Even though the worn portion is mended the appearance of the stocking is 15 unsightly and is often soon discarded causing expense and waste.

One object of my invention is to provide a stocking with a folded part which, when the knee portion becomes worn or torn, 20 can be readily let out so that said portion can be moved into a position where it will not ordinarily be visible and an unworn portion will take its place at the knee.

Another object is to so make my improved 25 stocking that it can be quickly and cheaply manufactured and so that it can be worn for a longer time than a stocking of usual construction, and will present a pleasing appearance.

These objects, and other advantageous 30 ends which will be described hereinafter, I attain in the following manner, reference being had to the accompanying drawings in which—

Figure 1 is a side elevation of a stocking made in accordance with my invention,

Figure 2 is an enlarged fragmentary section taken on the line 2—2 of Figure 1,

Figure 3 is a perspective view showing 40 my improved stocking and illustrating a hole at the knee portion, and

Figure 4 is a perspective view showing the same stocking as illustrated in Figure 3 having been altered or changed so that 45 the hole will occupy an inconspicuous position above the knee so that the knee of the wearer will be covered by an unworn portion of the stocking.

Referring to the drawing, the stocking 5 50 can be made in any manner, such for ex-

ample as of knit material and immediately above the heel 6 I form a tuck or folded portion 7 by folding the stocking telescopically as clearly shown in Figure 2 so as to provide a plurality of convolutions 8, 9 and 10. It will be noted that the leg or body portion 11 must be made sufficiently long to permit the formation of said folding and at the same time cover the knee of the wearer. I then sew the folds or convolutions together by a seam or stitching 12 preferably using a chain stitch so that the thread can be easily and quickly removed. The top folded edge 13 is preferably so located with respect to the foot 14 of the stocking that the shoe of the child will cover the entire folded portion.

If the knee portion 15 becomes worn, such for example as shown by the hole 16 in Figure 3 and it is desired that said hole will 70 not show, it is merely necessary to pull out the stitching of the seam 12 and move the body portion 11 relatively to the foot 14 so as to let out the convolutions of the fold or tuck and in so doing the hole 16 will be 75 moved away from the knee portion to such extent as shown in Figure 4 as to be above the knee and hence ordinarily invisible. It is of course understood that if desired the hole can be darned or mended so as to 80 prevent "runners" and it is obvious that an unworn portion will take its place at the knee so that it is practically impossible to distinguish the stocking from a new one.

Thus by forming the convoluted fold and 85 temporarily holding it with the stitching 12, it is possible to prolong the life of the stocking and at the same time allow the stocking to present a practically new appearance even after a hole has been worn at 20 the original knee portion.

While I have described my invention as taking a particular form, it will be understood that the various parts of my invention may be changed without departing from the 95 spirit thereof, and hence I do not limit myself to the precise construction set forth, but consider that I am at liberty to make such changes and alterations as fairly come within the scope of the appended claim. 100

Having thus described my invention, what I claim as new and desire to secure by Letters Patent is:—

A stocking having a folded part between the heel portion and the knee portion, the fold being secured in position by a removable line of stitching, substantially as described.

In testimony whereof I have signed my name to this specification in the presence of 10 two subscribing witnesses.

EVA LEPOW.
